UNITED STATES PATENT OFFICE

2,468,366

AUTOMATIC SHUTTER FOR FANS

Michael S. Habinski, Hamtramck, Mich.

Application November 25, 1947, Serial No. 788,005

3 Claims. (Cl. 98—116)

1

The present invention relates to new and useful improvements in fans for ventilating and other purposes and more particularly to an automatic shutter mechanism for the fan.

An important object of the invention is to provide an automatic shutter mechanism for ventilating fans and the like whereby the shutter will be normally held closed when the fan is not operating and will automatically open and its open position controlled by the speed of the motor shaft driving the fan.

A further object of the invention is to provide a governor-controlled shutter for fans which is simple and practical in construction, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view;

Figure 2 is a side elevational view;

Figure 3 is a top plan view with parts broken away and shown in section;

Figure 4 is an enlarged longitudinal sectional view of the governor; and

Figure 5 is a transverse sectional view taken on the line 5—5 of Figure 4.

Referring now to the drawings in detail wherein, for the purpose of illustration, I have disclosed a preferred embodiment of the invention, the numeral 5 designates a fan driven by an electric motor 6 through a shaft 7 which projects rearwardly of the motor. The fan 5 works immediately behind a shutter frame 8 having a plurality of shutters 9 positioned therein and swingable vertically at their rear edges on pins 10 carried by the side edges of the frame. The shutters are connected to each other for uniform opening and closing movement by a vertical rod 11 having right angled portions 12 extending transversely through apertured brackets 13 secured to the front outer edges of the shutter.

The pivot pin for one of the shutters is fixed thereto and is formed at one end with a crank 14 outwardly at one side of the frame and to which the front end of a link 15 is pivotally attached. The rear end of the link is pivoted to one end of a rocker arm 16 by means of clamps 17 and a ball and socket connection 18. The other end of the rocker arm is secured to the

2

motor 6 by means of a link 19 attached to the motor by means of a clamp 20.

The rocker arm 16 is provided intermediate its ends with a substantially square-shaped frame 21 having longitudinally extending slots 22 in a pair of its opposed sides and in which trunnions 23 at diametrically opposite sides of a block 24 are slidably positioned. The trunnions 23 project radially from diametrically opposite sides of a ring 25 which is seated in an annular groove 26 in the periphery of the block 24, the block being rotatable relative to the ring and trunnions 23.

The block 24 is slidably and rotatably carried at the rear end of the motor shaft 7 and secured to the shaft adjacent its inner end is a collar 27 connected to the block by resilient governor arms 28 having weights 29 at their central portions. A coil spring 30 surrounds the shaft 7 with one end bearing against the block 24 and its other end bearing against the collar 27.

In the operation of the device, the spring 30 normally slides the block 24 outwardly or rearwardly on the shaft 7 to thus rock the arm in a direction to exert a rearward pulling force on the link 15 whereby to rotate the crank 14 and to swing the shutters 9 downwardly into a closed position in the frame 8 in front of the fan 5 as shown by the full lines in Figure 2 of the drawing.

When the fan 5 is rotated by the motor 6 and shaft 7, the governor arms 28 will ride outwardly as shown by the dotted lines in Figure 4, whereby to draw the block 24 forwardly which carries with it the rocker arm 16, thus pushing the link 15 forwardly and rotating the crank 14 in a direction to swing the shutters 9 upwardly into the position as shown by the dotted lines in Figure 2.

The opening and closing movement of the shutter is thus controlled by the speed of the motor.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. In combination, a fan including a motor

having a shaft projecting rearwardly therefrom, a shutter pivoted in front of the fan, a governor carried by the shaft, and including a sliding block, a rocker arm pivotally supported at one end to a supporting structure, means connecting the other end of the arm to the shutter for opening and closing the shutter, and means connecting the sliding block to the rocker arm, said means comprising an annular groove in the sliding block, a ring seated in the groove, trunnions projecting radially from the ring, and a polygonal frame carried by the rocker arm and having slots in a pair of its opposed sides receiving the trunnions.

2. In combination, a fan including a motor having a shaft projecting therefrom, a governor on said shaft including a sliding block, a frame at one side of the motor, a crank shaft journaled in said frame to be rocked therein, a shutter on said crank shaft adapted to be opened and closed by rocking of said crank shaft, a rocker arm, means pivotally connecting said arm at one end to the motor, a link connection between the other end of said arm and the crank of the crank shaft, and means operatively connecting the slide block to said arm intermediate the ends of the arm.

3. In combination, a fan including a motor

5
10

having a shaft projecting therefrom, a governor on said shaft including a sliding block, a frame at one side of the motor, a crank shaft journaled in said frame to be rocked therein, a shutter on said crank shaft adapted to be opened and closed by rocking of said crank shaft, a rocker arm pivotally connected at one end to the motor, means operatively connecting the other end of said arm to the crank of the crank shaft, and means operatively connecting the slide block to said arm intermediate the ends of said arm, the pivotal connection of the rocker arm to the motor including a link compensating for rocking of said arm.
